1876. L. No. Samuel Hollott of San Francisco Cal. DES. 2439
Letters Patent No. 2439. Dated Sept. 25, 1866.
Proof in Design for a Centre Piece.

What is referred to in this Letters Patent and making part of the same.

To all whom it may concern,

Be it known that I, Samuel Hollott of the City and County of San Francisco, State of California, have originated and designed a new "Centre Flower" for buildings in alto reliefs in which the following is a full, clear, and exact description, preference being had to the accompanying drawings making part of this specification.

B. is a photograph of a centre flower of my design composed of plaster of paris, so called, cast and modeled in the usual way well known to workers in stucco, with the exception, I prefer to cast the different portions in gelatinous moulds instead of plaster, as this manner of casting imparts a higher degree of relief to the figures and brings out the design with greater distinctness.

My said design is composed of four arms joist to a central shield. At each end of the arms is placed a puerapple.

Alternately, between the arms I place a stone of stucco work leaves and flowers consisting of a posseture clasped with a bunch of grapes upon each side of, and partially enclosed in the wall work, projecting a little from the edge. — The centre piece is attached in the usual way.

Having thus described my Design for Centre Flower, what I claim, and desire to secure by Letters Patent is,

The Design or Pattern herein set forth, for the purpose specified.

Witness whereof I have hereunto set my hand and seal this 7th day of August, 1866.
